UNITED STATES PATENT OFFICE.

EDWIN G. BUSSE AND ERNEST A. LE BEAU, OF CHICAGO, ILLINOIS, ASSIGNEES TO
CHICAGO RAILWAY EQUIPMENT COMPANY, OF CHICAGO, ILLINOIS, A CORPORA-
TION OF ILLINOIS.

ROLLER SIDE BEARING FOR RAILWAY-CARS.

1,148,145.

Specification of Letters Patent. Patented July 27, 1915.

Application filed May 16, 1914. Serial No. 839,015.

To all whom it may concern:

Be it known that we, EDWIN G. BUSSE and ERNEST A. LE BEAU, citizens of the United States, residing at Chicago, Illinois, have invented a certain new and useful Improvement in Roller Side Bearings for Railway-Cars, of which the following is a full, clear, and exact description, such as will enable others skilled in the art to which it appertains to make and use the same, reference being had to the accompanying drawings, forming part of this specification, in which—

Figure 1 is a side elevational view partly in horizontal section of our improved roller side bearing for railway cars. Fig. 2 is a bottom plan view. Fig. 3 is a vertical cross sectional view. Fig. 4 is an end view of the main housing.

This invention relates to a new and useful improvement in roller side bearings for railway cars of the single roller type having centering means preferably in the form of springs whose energies are normally exerted to center said roller. There is also a removable end member or closure which, when in position, after the parts have been assembled, prevents the parts from becoming accidentally dismantled.

While we have shown an inverted bearing designed especially to be attached to the body bolster of the car, it is obvious that this bearing could be used on the truck bolster, in which event the roller would be presented upwardly and dirt exits would be provided at each end of the main casting preferably in line with the surface of the track plate.

In the drawings 1 indicates a casting having attaching lugs or ears 2 extending from its base portion. The track plate 3, preferably of hardened steel, is secured to the inner side of the base portion. The side walls of the casting are formed with inwardly presented grooves 4 in which is slidably arranged engaging portions or flanges provided on a carriage 5, said carriage having spring centering teats 6 with which cooperate springs 7 seated in pockets 8 formed in the end walls of the casting.

9 is an axle whose ends are mounted in upwardly opening recesses or bearing seats in the carriage 5, and 10 is the roller mounted on the axle within the carriage and co-

operating with the track plate 3. The periphery of this roller extends beyond the plane of the edges of the carriage. One of the end walls 11 of the main casting is removably mounted in position being held in place by bolts 12. This end wall when in position closes one end of the guiding grooves in the main casting and when removed permits the bearing to be dismantled for purposes of repair or renewal of the parts. The bearing members illustrated as 65 an axle 9 may be either an independent axle keyed in the roller 10, or may be trunnions formed integrally with the roller.

In the operation of assembling the parts of the device the removable end wall or closure 11 is removed by disengaging the bolts 12, and when thus removed the carriage 5 can be readily introduced into the casing with its flanges disposed in the grooves 4, it being understood that before introducing the carriage into place the roller is properly positioned by passing the ends of its axle downward into the upwardly opening bearing seats provided in the carriage. After the carriage has been thus mounted in the 80 casing and the centering springs arranged in place, the end wall 11 is secured in place by the bolts 12, and thus serves to prevent escape of the carriage from the casing, it being understood of course, that the carriage 85 can be introduced into the casing only by an endwise entrance of the engaging flanges into the grooves 4. It is apparent from the foregoing that there is provided a simple construction wherein the parts can be readily assembled or dismantled should circumstances require, and this by the simple expedient of removing the end wall 11.

Although we have shown a form employing but one roller, it is evident that the carriage may be formed to carry two or more rollers mounted and operating therein in fashion similar to the one shown. We are aware also that other changes and modifications may be made in the device without departing from the scope of the invention.

We claim:

In a side bearing for railway cars, a casting having a track surface for the engagement of a roller, said casting being provided with inwardly opening longitudinally disposed guide ways in its side walls, said guide ways being open at one end of the

casing and closed at the opposite end by the integral end wall of said casing, a carriage open at its top and bottom and provided with open ended recesses in the inner faces of its side walls to form blind bearings and permit vertical movement of the roller axle in said bearings, said carriage also having laterally extending portions entering the guide ways in the casing, a roller 10 designed to engage and coöperate with the track surface of the casing and having bearing portions coöoperating with the blind bearing seats in the carriage, springs for normally centering the carriage in the cas-

ing, a removable end wall or closure for one end of the casing forming a seat for one of said springs and a closure for said guide ways in the casing, and means for detachably securing said end wall in position.

In testimony whereof we hereunto affix our signatures in the presence of two witnesses, this 12th day of May, 1914.

EDWIN G. BUSSE.
ERNEST A. LE BEAU.
